RADIO SHIELDING MEANS

Melville F. Peters, Beltsville, Md.

Application May 11, 1938, Serial No. 207,416

7 Claims. (Cl. 123—148)

(Granted under the act of March 3, 1883, as
amended April 30, 1928; 370 O. G. 757)

This invention relates to means for shielding the ignition system of an internal combustion engine to prevent interference with the operation of radio receiving sets due to energy radiated from such ignition system, and more particularly to apparatus adapted to be used on an aircraft in conjunction with the metal cowling for the engine and the metal of the nacelle.

Among the several objects of this invention 10 are:

To provide simple and effective means for preventing radiation from the ignition system of an internal combustion engine;

To provide means for shielding an ignition system wherein the metal of surrounding parts of the structure in which the ignition system is installed assists in the shielding function;

To provide radio shielding means that will introduce no difficulties due to retention of heat 20 by the shielding means;

To utilize readily formed shapes of foraminous electrically conducting material around certain of the parts to be shielded.

Further objects of this invention will become 25 apparent from the description that follows.

In the drawings:

Fig. 1 discloses one embodiment of my invention wherein the magneto and certain other elements are enclosed in a foraminous electrically 30 conducting shield and the ignition leads are grounded thereon;

Fig. 2 shows a variation of my novel shielding means wherein substantially flat members in the form of shielding walls are disposed on opposite sides of the magneto and certain other parts and 35 are grounded on the engine cowling;

Fig. 3 shows novel means for suppressing very short waves.

In Fig. 1 there is depicted, by way of illustration, an aircraft engine 3 mounted in a metal nacelle 4 and having disposed around it metal cowling 5. Ignition current is supplied to the cylinders 6 by way of ignition leads 7 from a magneto 8. A ring 9 is disposed around and grounded to the engine 3 and a foraminous metallic enclosure 10 substantially in the form of a cylinder closed at one end is disposed around the magnetos 8 with the open end thereof closed by and grounded to the ring 9. That portion of each ignition lead 7 that lies outside the member 10 is enclosed in a conductive shielding element 11 that is grounded at one end to the engine adjacent the respective spark plug and at the other end to the ring 9 or to the member 10, as is most convenient in view of the position of the lead. While the return current could pass through the engine back to the magneto the well known proximity effect results in its following the path through the shielding elements 11. It is obvious that all radiation from the magnetos

and associated devices and from those parts of the leads 7 within the member 10 will be effectively intercepted by the member 10, the ring 9 and the portion of the engine structure within the member 10. It is known that if the return 5 current passes through the engine there is resultant radiation and interference with radio equipment adjacent thereto.

The embodiment of my invention shown in Fig. 2 differs from that in Fig. 1 in that the 10 foraminous conducting member 15 extends completely across the space within cowling 5 in the form of a wall, rearwardly of the magneto 8. A second wall or foraminous shielding member 12, extends from the cowling to engine 3 forwardly of magneto 8, it being understood that both of members 15 and 12 are electrically 15 grounded to the cowling 5 and that member 12 is also grounded to engine 3. Here, as in Fig. 1, the ignition lead 7 is shielded exteriorly of the 20 space between members 15 and 12 by well-known flexible shielding elements 11 that are grounded at one end to the engine and at the other end to the foraminous members.

It has been found that adequate shielding is 25 had when the mesh of members such as 12 is sufficiently large that there is no appreciable increase in air resistance due thereto. There are numerous advantages inherent in my present invention not found in the types of shielding 30 heretofore known wherein the ignition wires are carried in a rigid shielding manifold. Among such advantages are ease of removing and replacing ignition leads, the absence of outlets that may result in bends in the leads, ready access 35 of air to the shielded parts to carry off heat conducted thereto from the engine and a great degree of freedom in disposing the leads in a manner that is most convenient and advantageous for installation. It is desirable that all metal 40 parts such as 13 and 14, whatever their nature, that extend out from the space between the foraminous shielding members 15 and 12 should be grounded to such members whereby to prevent their carrying any stray radiation into 45 unshielded space.

It has been found that a considerable degree of shielding results from metallic parts disposed around the ignition system in such position that radiation therefrom is prevented from passing 50 out into space by repeated reflection from such metallic parts. That is, the auxiliary apparatus such as carburetors, pumps, oil lines, etc., all aid in the shielding and if the leads are shielded from the magneto to the spark plug most of the 55 noises are cut off even if the magneto is not itself shielded although it is preferable that this be done.

The radiation from an ignition system consists of several frequencies. That resulting from the 60

ignition current has a frequency of from 4 to 10 megacycles and is adequately suppressed by the shielding means above described. However, the capacity of the spark plug is such that it sets up waves having a length of around one meter, that is, less than the usual length of the shielding apparatus, and radiation of such waves is not prevented by any of the shielding means heretofore used so far as is known to me. However, I have found that if a resistor 16 of suitable value be inserted between the center electrode 17 of the spark plug and the conductor 18 of the ignition lead, that these waves of length less than the length of the shielding apparatus are likewise suppressed. If such resistor be of too great value, it tends to damp out the long waves and the ignition spark is too weak. My experiments have shown that if such resistor have a value of about 100 ohms it renders the very short waves apertodic and effectively prevents radiation thereof, while it does not appreciably affect the strength of the ignition current.

The invention herein described and claimed may be used and/or manufactured by or for the Government of the United States of America for governmental purposes without the payment of any royalties thereon or therefor.

I claim:

1. Radio shielding means for the ignition system of an internal combustion engine, said system including a source of ignition current, comprising a plane ring disposed around the engine between the cylinders thereof and said source, said ring being mechanically and electrically connected to the engine, a foraminous electrically conducting member cooperating with said ring and the engine to enclose said source and grounded on said ring, conducting leads extending from said source through said ring and other leads from said source extending through said member, and a shielding element around each such lead, each said element being grounded at one end on said ring or on said member, respectively, and at the other end to the ground connection of the respective conductor.

2. Radio shielding means for the ignition system of an internal combustion engine having combustion chamber means and spark plug means therein, said system including a source of ignition current, comprising a plane ring disposed around the engine between the said combustion chamber means and said source, a foraminous electrically conducting member cooperating with said ring and engine to enclose said source and grounded on said ring, conducting leads extending from said source through said ring to said spark plug means, a resistive element between each conducting lead and the spark plug means to which it supplies current, and a shielding element around each such lead, each said shielding element being grounded at one end on said ring and at the other end on the spark plug shell.

3. Radio shielding means for the ignition system of an aircraft internal combustion engine, said system including a source of ignition current, comprising the combination with cowling around said engine of an electrically conducting foraminous screen extending across the space within said cowling at one side of said source and grounded to said cowling, a second like screen on the other side of said source extending from said cowling to said engine and grounded to both, and shielding elements around electrically conducting members extending through either said

screen, said shielding elements being each grounded at one end to the respective screen and having the other end also grounded.

4. Radio shielding means for the ignition system of an aircraft internal combustion engine having spark plugs, said system including a source of ignition current, comprising the combination with cowling around said engine of an electrically conducting foraminous screen extending across the space within said cowling at one side of said source and grounded to said cowling, a second like screen on the other side of said source extending from said cowling to said engine and grounded to both, conducting leads from said source to said spark plugs, a resistive member in series between each such lead and its respective spark plug, and a shielding element around each said lead grounded to a said foraminous member and to the shell of the respective spark plug.

5. Radio shielding means for the ignition system of an aircraft internal combustion engine having spark plugs, said system including a source of ignition current, comprising the combination with cowling around said engine of an electrically conducting foraminous screen extending across the space within said cowling at one side of said source and grounded to said cowling, a second like screen on the other side of said source extending from said cowling to said engine and grounded to both, conducting leads from said source to said spark plugs, a resistive member in series between each said lead and its respective spark plug, the value of said resistive member being sufficient to suppress waves of the order of those due to the capacitance of the spark plug but insufficient to reduce the current detrimentally, and a shielding element around each said lead grounded to a said foraminous member and to the shell of the respective spark plug.

6. Radio shielding means for the ignition system of an aircraft internal combustion engine having spark plugs, said system including a source of ignition current, comprising the combination with cowling around said engine of an electrically conducting foraminous screen extending across the space within said cowling at one side of said source and grounded to said cowling, a second like screen on the other side of said source extending from said cowling to said engine and grounded to both, conducting leads from said source to said spark plugs, a resistive member in series between each said lead and its respective spark plug, the value of said resistive member being sufficient to suppress waves of length not substantially greater than the distance between a said foraminous member and the spark plug, and a shielding element around each said lead grounded to a said foraminous member and the spark plug shell.

7. Radio shielding means for the ignition system of an internal combustion engine, said system including a source of ignition current, comprising a foraminous electrically conducting member cooperating with said engine substantially to enclose said source and grounded through said engine, conducting leads extending from said source through said member and a shielding element around each such lead, each said element being grounded at one end on said member and at the other end to the ground connection of the respective conductor.
